BLIND STITCH SEWING MACHINE FOR
SEAMING HEMSCharles W. Mueller, St. Louis, Mo., assignor to
Lewis Invisible Stitch Machine Company, St.
Louis, Mo., a corporation of Maine

Application January 17, 1934, Serial No. 707,029

39 Claims. (Cl. 112—177)

This invention relates to new and useful improvements in blind stitch sewing machines for seaming hems or other superposed fabric layers. Heretofore hems have been stitched by a line of single thread blind stitches wherein all of the needle thread loops have joined the hem to the body fabric or base layer and have been laid in a manner to simulate hand made whip stitches. By reason of all the needle thread loops being anchored to the body fabric, a puckering or wavy effect is given to them, and this effect is undesirable particularly in narrow hems which are formed along the bottoms of waists and skirts. This undesirable effect was overcome by me as shown in my seam Patent 1,903,933 which issued April 18, 1933, wherein alternate needle thread loops enter and emerge from the upper face of the body fabric below the hem and also penetrate upwardly through the hem, the remaining needle thread loops penetrating upwardly through the hem only, thereby avoiding the puckering or wavy effect which would otherwise occur. However, in hemming blouses considerable trouble has been encountered at the beginning and ending of each hemming operation owing to the fact that at times the first and last stitches, which are known as "anchor" stitches, may not engage the body fabric and therefore the hem will not be joined to the body fabric at these points.

One of the objects of this invention is to overcome this objection, and this I have accomplished by forming several "anchor" stitches in succession at the beginning and at the ending of the hemming operation, and forming therebetween a series of alternate "skip" and "anchor" stitches.

Another object of my invention is to provide in a blind stitch sewing machine having means for normally projecting both the hem and the body fabric and then the hem only into needle penetrating position whereby alternate "anchor" and "skip" stitches will be formed, a manually controllable means for positively insuring several "anchor" stitches to be formed in succession whenever desired.

A further object of the invention lies in the provision of a visible indicator for indicating to the operator whether the machine will form all "anchor" stitches, or alternate "anchor" and "skip" stitches.

With these and other objects in view which will more fully appear, the nature of the invention will be more clearly understood by following the description, the appended claims, and the

several views illustrated in the accompanying drawings.—

In the drawings:—

Figure 1 is a top plan view of a sewing machine constructed in accordance with my invention, 5

Figure 2 is a front elevation thereof,

Figure 3 is an elevation of the right hand side of the machine,

Figure 4 is an elevation of the left hand side of the machine, parts thereof being shown in 10 section,

Figure 5 is a bottom plan view of the pivoted work support and the mechanism mounted thereon,

Figure 6 is a top plan view of the pivoted work 15 support with a portion thereof being shown in horizontal section to better disclose the mechanism mounted on the under side thereof,

Figure 7 is a view partly in elevation and partly 20 in section showing the mechanisms for driving the lower feed dog and for oscillating the cam-shaft of the ridge forming plunger,

Figure 8 is a bottom plan view of the laterally extending and the forwardly extending arms, together with the mechanisms contained therein, 25

Figure 9 is a detail horizontal section of the driving eccentrics on the main shaft,

Figure 10 is a detail rear view showing the 1-to-2 driving connections for the cam-shaft of the 30 ridge forming element,

Figure 11 is a vertical sectional view showing the free mounting of one of the differential gear units on the main shaft,

Figure 12 is a side elevation showing the disc, the eccentric and the eccentric sleeve of the 35 ridge forming element driving means,

Figure 13 is an end elevation of the preferred type of lower feed dog,

Figure 14 is a side elevation thereof,

Figure 15 is a perspective view showing the 40 various parts of said feed dog in separated relation,

Figure 16 is a side elevation of a modified form of lower feed dog,

Figure 17 is an end elevation thereof,

Figure 18 is a perspective view showing the various parts of said modified feed dog in separated relation,

Figure 19 is a vertical sectional view showing 50 the mounting of the transmitting lever,

Figure 20 is an enlarged top plan view of the stationary presser foot, and cooperating parts,

Figure 21 is a vertical section showing the 55 manually operable lever shifted to effect an al-

ternate shifting of the range of movement of the ridge forming element.

Figure 22 is a detail view showing the corresponding position of the cam which raises and lowers the ridge form element.

Figures 23 to 30 are similar pairs of views showing the parts in various positions.

Figure 31 is a detail front view showing the substitution of a disc-carrying shaft for the cam-carrying shaft.

Figure 32 is an end elevation of the disc.

Figure 33 is a plan view of a body fabric hemmed by my invention.

Figure 34 is a sectional view taken on the line 15 34-34 of Figure 33, and

Figure 35 is a sectional view taken on the line 35-35 of Figure 33.

Like reference numerals designate corresponding parts throughout the several figures of the drawings.

By reference to Figures 33, 34 and 35 of the drawings, it will be seen that a body fabric or base layer A is formed with a hem B extending along one edge thereof, the hem including a hem fold b and an inturned edge portion b'. The hem is joined to the body fabric by a line of single thread stitches. The thread C is formed into a series of connected needle thread loops which are equally spaced apart. The loops c join both the body fabric and the hem and are called "anchor" stitches, whereas the loops c' do not engage the body fabric but enter and emerge from the hem only and are called "skip" stitches. While the fabric is being fed through the machine, the hem B is first joined to the body fabric A by several successively formed "anchor" stitches, then a series of alternate "skip" and "anchor" stitches are made along the hem, and then at the ending of the operation the hem is again joined to the body fabric by several successively formed "anchor" stitches. Thus, the major portion of the hem is joined by alternate "skip" and "anchor" stitches which avoid the wavy or puckering effect heretofore explained, and the end portions of the hem are properly joined to the body fabric by several successively formed "anchor" stitches.

My improved sewing machine for forming the hem seam just described, includes a frame comprising a base 5 having a standard 6 rising from the rear right hand corner thereof, and integral with the upper end of the standard is an arm 7 which extends laterally towards the left and terminates in a forwardly extending arm 8. A pair of spaced posts 9, 10 are integral with the base 5 and project upwardly therefrom, said posts being disposed in front of the arm 7 and at the right of the arm 8, and are disposed in a vertical plane in substantially parallelism with the longitudinal axis of the arm 7.

60 A stationary presser foot 11 is removably attached to the front end of the arm 8 by a clamping screw 12. Vertical arms 11a, 11a cooperate with the arm 8 and the foot to hold the latter against flexing. An edge guide 11b for the hem is attached to the front of the foot.

70 A work support or plate 13 is pivoted on the posts 9, 10 through the medium of a pivot shaft 14 which is mounted in the posts and secured therein against rotation by set screws 15, the ends of the shaft having pivotal connection with lugs 16, 16 depending from the work support 13, as shown in Figure 5. The pivot shaft 14 is located centrally between the front and rear edges of the work support in order to permit the front portion

5 of said support to be rocked upwardly and downwardly relative to the stationary presser foot 11. A block 17 is rigidly secured to the left hand end of the work support 13 by screws 17a and is disposed directly under the presser foot. The forward portion of the work support is urged upwardly towards the presser foot by a coil spring 18 which is coiled around the pivot shaft 14, one end 19 resting against a lug 20 which depends from the work support and the other end 21 extending 10 downwardly into engagement with an adjusting screw 22 threadably engaged in a lug 23 on the base 5. The rear portion of the work support is limited in its downward movement by an adjusting screw 24 threadably engaged in the work sup- 15 port and having its lower end normally engageable with a bearing lug 25 integral with the standard 6. The screw 24 is provided with a head 26 having a circular series of notches 26a on its lower face for engagement by a spring detent 27 20 mounted in the work support to retain the screw in an adjusted position. A pointer 28 is mounted on the work support for vertical adjustments and is clamped in position by a screw 30a, and this pointer overhangs the head 26 of the screw 24 25 for cooperation with a scale 29 for guiding the operator in predetermining the height of the forward portion of the work support 13 relative to the presser foot 11, and for limiting the upper extreme position of the forward portion of the 30 work support for a purpose hereinafter described.

Journalized in the arm 7 of the frame and extending longitudinally thereof is a rotary main or drive shaft 30 to which power is applied through the medium of a belt wheel 31 fixed on said shaft. 35 Journalized in the forwardly extending arm 8 and extending longitudinally thereof is an oscillatory needle shaft 32 which is driven from the main shaft by the usual connection indicated as a whole by the numeral 33. Fixed to the front end of the 40 shaft 32 is a radially extending needle arm 34 to which is secured a curved needle 35. The needle thus reciprocates directly above the foot 11 and in a path transverse to the longitudinal axis thereof, the forward or work penetrating stroke being 45 from left to right. Cooperating with the needle 35 to form a series of connected single thread chain stitches is a 6-motion looper 36 which is driven from the main shaft 30 by the usual connections designated as a whole by the reference 50 numeral 37.

Journalized in lugs 38, 39 depending from the work support 13 and extending in parallelism with the pivot shaft 14 thereof, are spaced upper and lower rock shafts 40, 41, the former constituting a "feed travel" shaft and the latter constituting a "feed lift" shaft. The "feed lift" shaft 41 is rocked from the main shaft 30 through the medium of a depending rock arm 42 fixed to the right hand end of said shaft 41, and a pitman 43 60 which is pivoted at its forward end to the rock arm and is connected at its rear end to an eccentric 44 fixed to the main shaft 30. The "feed travel" shaft 40 is rocked from the main shaft 30 through the medium of a depending rock arm 45 fixed to 65 the right hand end of said shaft 40, and a pitman 46 which is pivoted at its forward end to the rock arm and is connected at its rear end to an adjustable throw eccentric 47 fixed to the main shaft. 70 The construction of the eccentric 47 is substantially identical with that disclosed in my Patent 1,903,932 which issued April 18, 1933, and therefore a specific description thereof is thought to be unnecessary.

An intermittent 4-motion lower feed dog 48 cooperates with the bottom of the presser foot 11 to feed the hemmed goods up to and past the needle. This feed dog is shown particularly in Figures 13, 14 and 15 and is mounted for lateral rocking on a carrier 49. The carrier 49 comprises spaced longitudinal walls 50, 51 which are rigidly connected across their upper edges by a cross bar 52 which is rectangular in cross section and 10 comprises vertical side faces 53, 53 and a horizontal flat face 54. The feed dog 48 comprises spaced longitudinal feed sections 55, 55 which are rigidly connected along their lower edges by spaced cross bars 56, 56 having flat vertical inner surfaces 57, 57 which engage the faces 53, 53 of the carrier and thereby retain the dog in longitudinal alignment with the carrier 49. A longitudinally and centrally extending horizontal pivot pin 58 rockably connects the dog 48 to its carrier 49, there being sufficient clearance between the dog and carrier to permit the former to rock about the pin as its axis. It will thus be seen that the cross bars 56, 56 of the dog form a resultant transverse space or groove for receiving the transverse bar or tongue 52 of the carrier and that this tongue and groove connection retains the dog against longitudinal movement relative to the carrier, while the pivot pin 58 permits the dog to rock laterally and thereby automatically accommodate the three thicknesses of the hem fold on one side and the single thickness of the body fabric on the other side and thus insure equal feeding action being given both to the hem fold and to the body fabric. It will be also observed that when a single thickness of fabric is fed through the machine, both feed sections 55 will clamp the work against the bottom of the foot with equal pressure.

In Figures 16, 17 and 18, I have illustrated a modified form of lower feed dog 59 comprising spaced longitudinal feed sections 60, 61 which are mounted on a carrier 62, the section 60 being integral with the carrier. The section 61 is provided with a shank 63 which is slidably mounted for vertical movements in a guiding groove 64 in the carrier. A keeper plate 65 covers the shank 63 and is attached to the carrier by screws 66. The lower end of the shank projects below the bottom of the carrier and is provided with a horizontal and open-ended slot 67 which receives the free end of a flat spring 68 which is connected to the carrier by a screw 69. Thus, the spring 68 functions not only to press the feed section upwardly, but also cooperates with the bottom of the carrier to limit the upward movement thereof. The lower extent of vertical movement of the feed section 61 is such that the feed surface thereof will be depressed below that of the relatively fixed feed section 60 when hemmed work is being fed through the machine, thereby insuring proper feeding action to the body fabric and to the hem.

The feed dog carrier 49 in the preferred construction, or the carrier 62 in the modified construction, is pivotally connected as at 70 to the upper end of a vertically disposed "feed-lift" link 71, the lower end of said link being pivotally connected as at 72 to an intermediate point on a lever 73 which extends substantially horizontally. One end of this lever is provided with a fork 74 which cooperates with a shoe 75 freely mounted on a pin 76 extending laterally from a rock arm 77 fixed to the "feed-lift" shaft 41. The other end of the lever 73 is pivotally connected as at 78 to the lower end of a vertically disposed post 79

which is mounted for vertical movements in the block 17 and carries at its upper end a rigidly connected work clamp 80 which is provided with the usual feed slots through which project the feed sections 55, 55 of the preferred construction 5 of feed dog or the feed sections 60, 61 of the modified construction of feed dog. The forward end of the lever 73, that is, opposite the fork 74 is urged upwardly by coil springs 81, 81 which have their lower ends connected to the pivot pin 10 18 and the upper ends extending into openings formed in the block 17, the upper ends of the springs being fixedly connected to said block whereby the work clamp 80 is yieldably held against the lower face of the presser foot 11 16 when the feed dog is not performing a feeding action. In order to impart backward and forward movement to the feed dog and thereby intermittently feed the work up to and past the needle 35, the feed dog 48 in the preferred form 20 or 59 in the modified form is pivotally connected as at 82 with one end of a substantially horizontally and rearwardly extending link 83, the rear end thereof being pivotally connected as at 84 to a substantially vertically extending rock arm 25 85 fixed to the "feed-travel" shaft 40. The carrier 49 is provided with a downwardly extending finger 86 and to the lower end of this finger is connected the upper end of a coil spring 87, the lower end of said spring being connected to the 30 "feed-lift" link 71. It will be noted that the eccentric 47 is located in registry with an opening 6a formed in the top of the standard 6, and that the opening is closed by a cover plate 6b which is swingable about a pivot screw 6c to an open 35 position whereby ready access may be had to the eccentric 47 whenever it is desired to adjust the feed stroke of the lower feed dog. This 4-motion feed mechanism is well known in the art and a further description thereof is thought to be 40 unnecessary.

In order to project a ridge of material into needle penetrating position immediately prior to each penetrating stroke of said needle, I have employed a vertically reciprocating ridge forming element or plunger 88 which is located below the presser foot 11 and in a vertical plane containing the path of needle oscillation, the plunger moving upwardly through a slot or opening 11c which extends longitudinally of the foot 50 from a point in front of the needle to a point well in rear thereof, and having a groove 80a in the upper end thereof. Means are provided for vertically reciprocating the plunger 88 and for alternately and bodily varying the position of 55 reciprocation of said plunger whereby the needle 35 on every other penetrating stroke will enter both the base layer A and the hem B to form the "anchor" stitches c and on alternate or intermediate strokes will enter the hem only to form 60 the "skip" stitches. Manually operable means are provided for maintaining constant the position of reciprocation of the plunger whereby the needle will successively penetrate both the base layer and the hem and thereby form a series of 65 successive "anchor" stitches. To this end, the plunger is attached to the upper end of a vertically reciprocating cam plate 89 which is mounted in a guide slot 90 in the block 17. The cam plate, above the block 17, is provided with an open-sided cam recess 91 for receiving a three point open face cam 92, the recess forming resultant upper and lower cam surfaces 93 and 94 respectively. The cam 92 is provided with a concentric or dwell portion 95 and eccentric or ac- 75

tive portions 96 one of the latter merging with the dwell portion 95 to form a high point 97. A shoulder 98 is formed on the cam plate 89 and a flat spring 99 which is attached to the block 17 5 engages the shoulder and serves to yieldably retain the plunger 88 against overthrow. The cam 92 is fixed to a rock shaft 100 which is mounted on and below the work support 13 and extends in parallelism with the main shaft 30. The left 10 hand end of the cam shaft 100 is journaled in a bearing plate 101 which is mounted in a vertical slot 102 in the block 17. The right hand end of the cam shaft is journaled on the left hand end of a bearing pin 103 which is threadably mounted in an eccentric bore 104 extending longitudinally of a bushing 105 mounted in a bore 106 in a lug 107 which is integral with and depends from the work support 13. The pin 103 is held in a previously adjusted position by a set 15 screw 108 which is threadably mounted in the bushing 105, and the bushing 105 is held in place by a set screw 109 which is threadably mounted in the lug 107. A driving eccentric 110 is fixed to the main shaft 30 and surrounding this eccentric is an eccentric sleeve 111 which is positively rotated on the eccentric but at one-half the speed thereof. A disc 112 which is loosely mounted on the main shaft 30 is provided with a radial slot 113 for receiving a slide block 114 20 fixed to the eccentric sleeve 111 by a shank 115 and a lock screw 116 which cooperates with the shank. A driving gear 117 is fixed to the main shaft 30, and freely rotatable on a stationary shaft 118 mounted in the frame standard 6 is a 25 gear unit comprising a large gear 119 and a smaller gear 120, the former being in constant mesh with the driving gear 117, and the latter being in constant mesh with a gear 121 fixed to the disc 112. The gear coupling ratio is such 30 that the eccentric sleeve 111 will be rotated once during every two revolutions of the main shaft 30.

In order to oscillate the cam shaft 100 from the eccentric 110 and the eccentric sleeve 111, I have provided the following driving connections:—Journalized in a bore 122 in a lug which depends from the work support 13 is a rotatable pivot shaft 123 whose longitudinal axis is disposed in parallelism with the cam shaft 100. This pivot shaft 123 is provided with a reduced outer end 124 which projects beyond the bearing lug and a collar 125 is secured thereon to limit the inward movement of said shaft. The inner end of the pivot shaft 123 is provided with an integral and longitudinally extending eccentrically disposed pin or fulcrum 123a. Secured by a set screw 126 to the pivot shaft adjacent the inner face of the bearing lug is a manually operable rock arm or lever 127 having a handpiece 128 extending from the upper end thereof and projecting upwardly through and beyond an opening 129 formed in the work support 13 whereby upon back and forth movement of said handpiece the pivot shaft 123 will be rocked. In order to retain this handpiece and thereby the pivot shaft 123 in either of its extreme positions of oscillation, there is provided a bushing 130 in the bearing lug directly above the pivot shaft 123. This bushing is provided with a bore 131 and slidably mounted in said bore is a stop pin 132 50 which is moved outwardly toward the rock arm or lever 127 by a spring 133 which is disposed within the bore between the pin and a closure plug 134 which is threadably engaged with the outer end of said bore. This pin is therefore 55 spring pressed inwardly and is engageable with

either of two seats 135, 136 formed in the adjacent face of said lever 127. Thus when the lever 127 is actuated, the eccentric pin 123a will be shifted laterally and the pivot shaft 123 together with the fulcrum pin 123a will be retained in either of its extreme positions of oscillation. Freely journaled on the eccentric pin 123a is a substantially vertically disposed 2-armed transmitting lever 137, and a link 138 is pivotally connected at one end to the upper arm of said lever 137 and at its other end to a rock arm 139 which is fixed to and depends from the cam shaft 100. A strap link 140 has one end fitting around the eccentric sleeve 111 and has the other end pivotally connected to the lower arm of the lever 137. 15

In the actual operation of the machine, the hem B will necessarily cover the plunger 88 and consequently the operator will not know when the plunger is at the "anchor" stitch position. I have fixed to the cam shaft 100 a radially extending indicator finger 141 which projects upwardly through an opening 142 in the work support 13. This finger is so positioned on the shaft that when the plunger moves to its highest elevation to effect a resultant "anchor" stitch, it 20 will be projected through the front end of the opening 142, and when the plunger moves to a lesser elevation to effect a resultant "skip" stitch, the finger will be projected through the rear end of the opening. Consequently, the operator will 25 know upon viewing the position of the finger relative to the opening, whether the machine is to make "anchor" stitches only, or both "anchor" and "skip" stitches.

Cooperating with the lower feed dog to feed the hemmed fabric rearwardly up to and past the needle 35 is a 4-motion top feed dog 143 which operates on the hem through the feed slot 11c in rear of the needle. This feed dog is rigidly connected to the front end of a lever 144 which 30 is disposed within and extends longitudinally of the frame arm 8. The lever 144 has a sliding pivotal connection with a stud 145 fixed to said arm 8, and the rear end of the lever is actuated by an adjustable eccentric 146 mounted on the 45 main shaft, said eccentric being similar to the eccentric 46 which drives the lower feed dog. Thus by adjusting these eccentrics 46 and 146, the stitch length may be varied, and the feed stroke of the top feed dog may be increased relative to the feed stroke of the lower feed dog and thereby take care of the fullness which is present 50 in hems.

In order to support not only the bulk of the work as it is being fed through the machine but also the hand of the operator, I have provided a rigid shelf 147 which is located in front of the work support 13 and is removably attached to the base 5 through the medium of bracket arms 148, 149, the shelf extending to the right as well as to the left of the presser foot 11. The shelf is spaced from the work support 13 a distance sufficient to permit the later to be depressed whenever it is desired to insert or remove the work. 55

From the foregoing, it will be understood that a hemmer of any type may be located on the shelf 147 in front of the presser foot, that the hemmed fabric will be fed through the machine in the usual way by the intermittent top and bottom feeds, and that the needle will enter and emerge from the material between feed movements. The plunger 88 is given one complete reciprocation for each needle oscillation or for each rotation of the main shaft 30. Normally, the plunger 88 is 60 first given an upward movement of such a height 75

that the needle will penetrate both the body fabric and then the hem to form "anchor" stitches as shown in Figs. 33 and 34, and is then given an upward movement of a lesser height whereby 5 the needle will penetrate the hem only as shown in Figs. 33 and 35. As a result of the 1-to-2 gear coupling between the main shaft 30 and the eccentric sleeve 111, the high points of the eccentric 110 and the sleeve 111 will register in one rotation 10 of the main shaft and will be diametrically opposite in the next rotation of the main shaft. Consequently, the cam shaft 100 and the cam 92 will be oscillated and the position of the angular range of movement thereof will be varied whereby 15 the height of the plunger stroke will be intermittently varied. When it is desired to produce a series of "anchor" stitches, the manually operable lever 127 will be rocked, thereby shifting the eccentric fulcrum pin 123^a of the transmitting lever 137 to shift the cam shaft 100 angularly whereby the concentric surface 95 of the cam will engage the wall of the cam opening 94 of the cam plate 89 and thus elevate the plunger 88 to the same height during every rotation of the main 20 shaft and thereby during each cycle project a ridge of the body fabric and the hem into needle penetrating position. Thus at the beginning of each sewing operation, the operator first shifts the lever 127 to the position shown in Figs. 21, 25 and 29 whereby "anchor" stitches will be formed, then after the formation of several of these "anchor" stitches the operator shifts the lever 127 to its normal position as shown in Figs. 23 and 27, whereby a series of alternate "anchor" and "skip" 30 stitches will be formed, and finally at the end of the operation the operator returns the lever to the first position whereby a series of "anchor" stitches will be formed.

Instead of employing a vertically reciprocating plunger, I may employ a reciprocating ridge forming disc 150 as shown in Fig. 31. The cam shaft 100 is removed and the disc shaft 151 together with the disc 150 is substituted. The disc is formed with a concentric edge 152 and with a radial front edge 153, and a recess 154 is formed at their juncture. The disc is oscillated so that when all "anchor" stitches are formed, the concentric edge 152 is disposed below the needle path whereby the latter will enter and emerge from the body fabric and the hem, whereas when the lever 127 is shifted the disc shaft will be shifted angularly so that the edge 152 and the recess 154 will be alternately positioned below the needle whereby alternate "anchor" and "skip" stitches will be formed. An indicator finger 141 is attached to the disc shaft and functions in the same manner as heretofore described.

It will be observed that the concentric edge 152 and the bottom of the recess 154 of the disc form peripheral surfaces of different radii which are arranged in tandem, the surface 152 constituting a high portion and the bottom of the recess 154 constituting a low portion. When the high portion of the disc is presented to the needle, the latter will enter and emerge from both layers of the fabric and thereby form "anchor" stitches, and when the low portion of the disc is presented to the needle the latter will enter and emerge from the upper or superposed fabric layer only to thereby form resultant "skip" stitches. Thus when the manually operable lever 128 is shifted to successively present the high portion of the disc to the needle, the effective depth of needle penetration in the fabric layers is constant and when said manually operable lever 128 is

shifted, the effective depths of needle penetrations will be varied. It will also be understood that when the recess 154 is presented to the needle, the lower surface thereof supports the fabric layers against the thrust of the needle when 5 "skip" stitches are being formed.

It will also be observed that by adjusting the work table 13 about its axis by means of the screw 26, the upward limit of movement of the plunger 88 or the disc 150 relative to the needle 35, may 10 be varied, thereby permitting the needle to pass entirely through the body fabric as shown in Fig. 34, or only partially therethrough. The location of the adjusting screw 26 makes it easy for the operator to effect the desired adjustment, especially when different thicknesses of fabric are employed.

It is of course to be understood that the details of structure and arrangement of parts may be variously changed and modified without departing from the spirit and scope of my invention, and I wish it to be understood that I believe I am the first to provide a blind stitch sewing machine for forming either a line of all "anchor" stitches or a line having some "anchor" stitches and some 25 "skip" stitches.

I claim:—

1. In a sewing machine for seaming hemmed fabrics, the combination with a stationary presser foot having an opening, of a needle mounted 30 above the foot for reciprocatory movements across the opening in the foot, means for intermittently feeding the fabric up to and past the needle, a ridge forming element for intermittently projecting a node of the hemmed fabric upwardly through the presser foot opening into needle penetrating position, means for actuating the ridge forming element including devices for intermittently projecting the body fabric and the hem and then the hem only into needle penetrating positions, and manually controlled means 40 cooperating with the ridge forming element actuating means for successively projecting both the body fabric and the hem into needle penetrating position. 45

2. In a sewing machine for seaming hemmed fabrics, the combination with a stationary presser foot having an opening, of a needle mounted above the foot for reciprocatory movements across the opening in the foot, means for intermittently feeding the fabric up to and past the needle, a ridge forming element for intermittently projecting a node of the hemmed fabric upwardly through the presser foot opening into needle penetrating position, means for actuating 50 the ridge forming element including devices for intermittently projecting both the body fabric and the hem and then the hem only into needle penetrating positions, said actuating means comprising a main shaft, an oscillatory shaft operatively connected to the ridge forming element, and driving connections between the main shaft and the oscillatory shaft including a transmitting lever rockable on a shiftable fulcrum, and a manually operable lever for shifting said fulcrum and for shifting the angular range of movement of said oscillatory shaft whereby the ridge forming element will successively project both the body fabric and the hem into needle penetrating 55 position. 65

3. In a sewing machine for seaming hemmed fabrics, the combination with a stationary presser foot having an opening, of a needle mounted above the foot for reciprocatory movements across the opening in the foot, means for inter- 70 75

- mittently feeding the fabric up to and past the needle, a ridge forming element for intermittently projecting a node of the hemmed fabric upwardly through the presser foot opening into needle penetrating position, means for actuating the ridge forming element including devices for intermittently projecting both the body fabric and the hem and then the hem only into needle penetrating positions, said actuating means comprising a main shaft, an eccentric fixed to said main shaft, an eccentric sleeve surrounding said eccentric, a reduction gear coupling between the main shaft and the eccentric sleeve, an oscillatory shaft operatively connected to the ridge forming element, and driving connections between the eccentric sleeve and the oscillatory shaft including a transmitting lever rockable on a shiftable fulcrum, and a manually operable lever for shifting said fulcrum and for shifting the angular range of movement of said oscillatory shaft whereby the ridge forming element will successively project the body fabric and the hem into needle penetrating position.
4. In a sewing machine for seaming hemmed fabrics, the combination with a stationary presser foot having an opening, of a needle mounted above the foot for reciprocatory movements across the opening in the foot, means for intermittently feeding the fabric up to and past the needle, a ridge forming element for intermittently projecting a node of the hemmed fabric upwardly through the presser foot opening into needle penetrating position, means for actuating the ridge forming element including devices for intermittently projecting both the body fabric and the hem and then the hem only into needle penetrating positions, manually controlled means cooperating with the ridge forming element actuating means for successively projecting both the body fabric and the hem into needle penetrating position, and an indicator operated by the ridge forming element actuating means for indicating to the operator when the element is successively projecting both the body fabric and the hem into needle penetrating position.
5. In a sewing machine for seaming hemmed fabrics, the combination with a stationary presser foot having an opening, of a needle mounted above the foot for reciprocatory movements across the opening in the foot, means for intermittently feeding the fabric up to and past the needle, a ridge forming element for intermittently projecting a node of the hemmed fabric upwardly through the presser foot opening into needle penetrating position, means for actuating the ridge forming element including devices for intermittently projecting both the body fabric and the hem and then the hem only into needle penetrating positions, said actuating means comprising a main shaft, an oscillatory shaft operatively connected to the ridge forming element, and driving connections between the main shaft and the oscillatory shaft including a transmitting lever rockable on a shiftable fulcrum, a manually operable lever for shifting said fulcrum and for shifting the angular range of movement of said oscillatory shaft whereby the ridge forming element will successively project both the body fabric and the hem into needle penetrating position, and an indicator finger fixed to the oscillatory shaft for indicating to the operator when the element is successively projecting both the body fabric and the hem into needle penetrating position.
6. In a sewing machine, a reciprocatory ridge

forming element, and means for actuating said element and for intermittently varying its range of effective movement including a manually controlled means for maintaining constant its effective range of movement.

7. In a sewing machine, a stationary presser foot having an opening, a reciprocatory needle operating in a fixed path above the opening, a reciprocatory ridge forming element located below the foot for projecting a ridge of material upwardly through the opening into needle penetrating position, and means for actuating said ridge forming element and for varying its range of effective movement whereby the ridge of material will be projected higher through the opening at one time than at another and including a manually controlled means for maintaining constant its effective range of movement whereby the ridge of material will be projected through said opening to the same height.

8. In a sewing machine, a reciprocatory ridge forming element, and means for actuating said element and for intermittently varying its range of effective movement including a manually controlled means for maintaining constant its effective range of movement, said actuating means comprising a main shaft, an oscillatory shaft operatively connected to the ridge forming element, and driving connections between the main shaft and the oscillatory shaft including a transmitting lever rockable on a shiftable fulcrum, and a manually operable lever for shifting said fulcrum and for shifting the angular range of movement of said oscillatory shaft whereby the ridge forming element will successively project both the body fabric and the hem into needle penetrating position.

9. In a sewing machine, a stationary presser foot having an opening, a reciprocatory needle operating in a fixed path above the opening, a reciprocatory ridge forming element located below the foot for projecting a ridge of material upwardly through the opening into needle penetrating position, and means for actuating said ridge forming element and for varying its range of effective movement whereby the ridge of material will be projected higher through the opening at one time than at another and including a transmitting lever, a shiftable fulcrum for the lever, and a manually operable lever for shifting said lever fulcrum for maintaining constant the effective range of movement of the ridge forming element whereby the ridge of material will be projected through said opening to the same height.

10. In a sewing machine, a stationary presser foot having an opening, a reciprocatory needle operating in a fixed path above the opening, a reciprocatory ridge forming element located below the foot for projecting a ridge of material upwardly through the opening into needle penetrating position, and means for actuating said ridge forming element and for varying its range of effective movement whereby the ridge of material will be projected higher through the opening at one time than at another and including a manually controlled means for maintaining constant its effective range of movement whereby the ridge of material will be projected through said opening to the same height, said actuating means comprising a main shaft, an eccentric fixed to the main shaft, an eccentric sleeve surrounding the eccentric, a reduction gear coupling between the main shaft and the eccentric sleeve, an oscillatory shaft operatively connected to the ridge forming

element, driving connections between the eccentric sleeve and the oscillatory shaft including a transmitting lever rockable on a shiftable fulcrum, and a manually operable lever for shifting the fulcrum of the transmitting lever for shifting the angular range of movement of said oscillatory shaft.

11. In a sewing machine, a reciprocatory ridge forming element, and means for actuating said element and for intermittently varying its range of effective movement including a manually controlled means for maintaining constant its effective range of movement, and an indicator operated by the ridge forming element actuating means for indicating to the operator when the element is successively projecting both the body fabric and the hem into needle penetrating position.

12. A plunger mechanism for sewing machines, comprising a vertically reciprocatory cam plate, a plunger fixed to said plate, a horizontal cam shaft having a cam fixed thereon and operatively engaged with the cam plate, and means for oscillating said cam shaft.

13. A plunger mechanism for sewing machines, comprising a vertically reciprocatory plunger, and means for normally and intermittently varying the effective height of the plunger strokes including manually controlled means for maintaining constant the effective height of said plunger strokes.

14. A plunger mechanism for sewing machines, comprising a vertically reciprocatory cam plate, a plunger fixed to said plate, a horizontal cam shaft having a cam fixed thereon and operatively engaged with the cam plate, and means for oscillating said cam shaft including devices for varying the angular range of movement of the cam whereby the height of the plunger stroke will be correspondingly varied.

15. A plunger mechanism for sewing machines, comprising a vertically reciprocatory cam plate, a plunger fixed to said plate, a horizontal cam shaft having a cam fixed thereon and operatively engaged with the cam plate, and means for oscillating said cam shaft including devices for varying the angular range of movement of the cam whereby the height of the plunger stroke will be correspondingly varied, said devices including manually controlled means for shifting the cam shaft angularly whereby the height of the plunger stroke will be constant.

16. A plunger mechanism for sewing machines, comprising a vertically reciprocatory cam plate, a plunger fixed to said plate, a horizontal cam shaft having a cam fixed thereon and operatively engaged with the cam plate, means for oscillating said cam shaft including a main rotary shaft disposed in parallelism with the cam shaft, and operating connections between the main shaft and the cam shaft including devices for varying the angular range of movement of the cam whereby the height of the plunger stroke will be correspondingly varied.

17. A plunger mechanism for sewing machines, comprising a vertically reciprocatory cam plate, a plunger fixed to said plate, a horizontal cam shaft having a cam fixed thereon and operatively engaged with the cam plate, means for oscillating said cam shaft including a main rotary shaft disposed in parallelism with the cam shaft, and operating connections between the main shaft and the cam shaft including devices for varying the angular range of movement of the cam whereby the height of the plunger stroke will be

correspondingly varied, said devices including manually controlled means for shifting the cam shaft angularly whereby the height of the plunger stroke will be constant.

18. A plunger mechanism for sewing machines, comprising a vertically reciprocatory cam plate, a plunger fixed to said plate, a horizontal cam shaft having a cam fixed thereon and operatively engaged with the cam plate, and means for oscillating said cam shaft including devices for varying the angular range of movement of the cam whereby the height of the plunger stroke will be correspondingly varied, said cam shaft oscillating means comprising a main shaft, driving connections between the main shaft and the cam shaft including a transmitting lever rockable about a shiftable fulcrum, and a manually operable lever for shifting said fulcrum and for angularly shifting said cam shaft whereby the height of the successive plunger strokes will be constant.

19. A plunger mechanism for sewing machines, comprising a vertically reciprocatory cam plate, a plunger fixed to said plate, a horizontal cam shaft having a cam fixed thereon and operatively engaged with the cam plate, and means for oscillating said cam shaft including devices for varying the angular range of movement of the cam whereby the height of the plunger stroke will be correspondingly varied, said cam shaft oscillating means comprising a main shaft, an eccentric fixed to the main shaft, an eccentric sleeve surrounding the eccentric, a reduction gear coupling between the main shaft and the eccentric sleeve, driving connections between the eccentric sleeve and the cam shaft including a transmitting lever rockable about a shiftable fulcrum, and a manually operable lever for shifting said fulcrum and for angularly shifting said cam shaft whereby the height of the successive plunger strokes will be constant.

20. A plunger mechanism for sewing machines, comprising a vertically reciprocatory plunger, means for intermittently varying the effective height of the plunger strokes including manually controlled means for maintaining constant the effective height of said plunger strokes, and an indicator operated by the cam shaft oscillating means for indicating to the operator when the height of the plunger stroke is constant. 50

21. A plunger mechanism for sewing machines, comprising a vertically reciprocatory plunger, means for intermittently varying the effective height of the plunger strokes including manually controlled means for maintaining constant the effective height of said plunger strokes, and an indicator finger fixed to the cam shaft for indicating to the operator when the height of the plunger stroke is constant. 55

22. In a sewing machine, an oscillatory ridge forming disc, and means for oscillating said disc for a fixed amount and for intermittently varying the position of the angular range of movement of said disc including manually controlled means for oscillating the disc in a constant position of 60 angular range of movement.

23. In a sewing machine, an oscillatory shaft, a ridge forming disc fixed to said shaft, a main shaft, and operating connections between said shafts including devices for varying the position 70 of the angular range of movement of the disc, said devices including manually controlled means for oscillating the disc in a constant position of angular range of movement.

24. In a sewing machine, an oscillatory shaft, a 75

- ridge forming disc fixed to said shaft, a main shaft, an eccentric fixed to the main shaft, an eccentric sleeve surrounding the eccentric, a reduction gear coupling between the main shaft and the eccentric sleeve, driving connections between the eccentric sleeve and the disc shaft including a transmitting lever rockable about a shiftable fulcrum for varying the position of the angular range of movement of the disc, and a manually operable lever for shifting said fulcrum and for shifting the angular position of the disc shaft whereby the angular range of movement of the disc will be constant.
25. In a sewing machine, an oscillatory ridge forming disc, means for oscillating said disc for a fixed amount and for intermittently varying the position of the angular range of movement of said disc including manually controlled means for oscillating the disc in a constant position of angular range of movement, and an indicator operated by the disc oscillating means for indicating to the operator when the angular range of movement of the disc is constant.
26. In a sewing machine, an oscillatory shaft, a ridge forming disc fixed to said shaft, a main shaft, operating connections between said shafts including devices for varying the position of the angular range of movement of the disc, said devices including manually controlled means for oscillating the disc in a constant position of angular range of movement, and an indicator finger fixed to the disc shaft for indicating to the operator when the angular range of movement of the disc is constant.
27. In a sewing machine, the combination with a frame, of a stationary presser foot attached thereto and having an opening, a stitch forming mechanism disposed above the foot and including a needle having its path of movement across the opening in the foot, means located below the foot for projecting a node of fabric upwardly through the opening in the foot into needle penetrating position, a main shaft journaled in the frame, driving connections between the main shaft and the ridge forming element for intermittently actuating the latter in timed relation with the needle, and means for intermittently feeding the fabric up to and past the needle including upper and lower feeds cooperating with the fabric and respectively having independent driving connections with the main shaft.
28. In a sewing machine, the combination with a frame, of a stationary presser foot attached thereto and having an opening, a stitch forming mechanism disposed above the foot and including a needle having its path of movement across the slot in the foot, means located below the foot for projecting a node of fabric upwardly through the opening in the foot into needle penetrating position, a main shaft journaled in the frame, driving connections between the main shaft and the ridge forming element for intermittently actuating the latter in timed relation with the needle, and means for intermittently feeding the fabric up to and past the needle including upper and lower feeds cooperating with the fabric and respectively having independent driving connections with the main shaft.
29. In a sewing machine, the combination with a frame, of a stationary presser foot attached thereto and having an opening, a stitch forming

mechanism disposed above the foot and including a needle having its path of movement across the opening in the foot, means located below the foot for projecting a node of fabric upwardly through the opening in the foot into needle penetrating position, a main shaft journaled in the frame, driving connections between the main shaft and the ridge forming element for intermittently actuating the latter in timed relation with the needle, and means for intermittently feeding the fabric up to and past the needle including upper and lower feeds cooperating with the fabric and respectively having independent driving connections with the main shaft, said connections for the feeding means being separate from the ridge forming element actuating means and each feeding connection including an adjustable eccentric for adjusting the feed stroke of the associated feed dog.

30. In a sewing machine, the combination with a frame, of a stationary presser foot attached thereto and having an opening, a stitch forming mechanism disposed above the foot and including a needle having its path of movement across the opening in the foot, means located below the foot for projecting a node of fabric upwardly through the opening in the foot into needle penetrating position, a main shaft journaled in the frame, driving connections between the main shaft and the ridge forming element for intermittently actuating the latter in timed relation with the needle, and means for intermittently feeding the fabric up to and past the needle including upper and lower feeds cooperating with the fabric and respectively having independent driving connections with the main shaft, said connections for the feeding means being separate from the ridge forming element actuating means and each feeding connection including an adjustable eccentric for adjusting the feed stroke of the associated feed dog, said eccentrics being mounted on said main shaft.

31. In a blind stitch sewing machine for seamming superposed fabric layers, the combination with a horizontal presser foot having an opening; of a stitch forming mechanism disposed above the foot and including a reciprocating needle movable above said opening; means for projecting a ridge of said fabric layers upwardly through the presser foot opening into needle penetrating position whereby during successive cycles the needle will enter and emerge from both layers to form resultant "anchor" stitches joining said layers, and manually operable control means for effecting the periodic lowering of said ridge relative to the path of needle movement whereby during certain cycles the needle will enter and emerge from the upper layer only to form resultant "skip" stitches.

32. In a blind stitch sewing machine for seamming superposed fabric layers, the combination with a horizontal presser foot having an opening; of a stitch forming mechanism disposed above the foot and including a reciprocating needle movable above said opening; means for intermittently projecting a ridge of said fabric layers upwardly through the presser foot opening into needle penetrating position whereby during successive cycles the needle will enter and emerge from both layers to form resultant "anchor" stitches joining said layers, and manually operable control means associated with said ridge projecting means for effecting the periodic lowering of said ridge relative to the path of needle movement whereby during certain cycles

the needle will enter and emerge from the upper layer only to form resultant "skip" stitches.

33. In a blind stitch sewing machine for seaming superposed fabric layers, the combination 5 with a horizontal presser foot having an opening; of a stitch forming mechanism disposed above the foot and including a reciprocatory needle movable above said opening; an element located below the path of needle travel for forming a ridge 10 of fabric; means for reciprocating said element for intermittently projecting both fabric layers upwardly through the presser foot opening into needle penetrating position whereby the needle during successive cycles will enter and emerge 15 from both layers to form resultant "anchor" stitches joining said layers, and manually operable control means for effecting the positioning of the ridge forming element at a lower height relative to the path of needle travel during certain cycles whereby the needle will enter and 20 emerge from the upper layer only to form resultant "skip" stitches.

34. In a blind stitch sewing machine for seaming superposed fabric layers, the combination 25 with a horizontal presser foot having an opening; of a stitch forming mechanism disposed above the foot and including a reciprocatory needle movable above said opening; an element located below the path of needle travel for forming a ridge 30 of fabric; means including an oscillatory shaft for reciprocating said element for intermittently projecting both fabric layers upwardly through the presser foot opening into needle penetrating position whereby the needle during successive cycles will enter and emerge from 35 both layers to form resultant "anchor" stitches joining said layers, and manually operable control means for varying the position of the angular range of movement of said shaft for effecting the 40 positioning of the ridge forming element at a lower height relative to the path of needle travel during certain cycles whereby the needle will enter and emerge from the upper layer only to form resultant "skip" stitches.

45 35. In a blind stitch sewing machine, an oscillatory ridge forming disc having peripheral surfaces of different radii arranged in tandem, a needle reciprocating above the disc, means for reciprocating the needle, means for oscillating the disc in timed relation to the needle reciprocations to thereby successively present one only of said disc surfaces to the needle to maintain constant the effective depth of needle penetration, and manually controlled means for effecting during the running of the machine the periodic presentation of one of said disc surfaces to the needle during certain cycles and the presentation of the other disc surface to the needle during other cycles to thereby vary the effective depths of 50 needle penetrations.

60 36. In a blind stitch sewing machine, the combination with a main shaft, of an oscillatory shaft, a ridge forming disc fixed thereto and having peripheral surfaces of different radii arranged in tandem, a needle reciprocating above the disc, means for reciprocating the needle, driving connections between said shafts for os-

cillating the disc in timed relation to the needle reciprocations to thereby successively present one only of said disc surfaces to the needle to maintain constant the effective depth of needle penetration, and manually controlled means associated with said driving connections for effecting the presentation of one of said disc surfaces to the needle during certain cycles and the presentation of the other disc surface to the needle during other cycles to thereby vary the effective 10 depths of needle penetrations.

37. In a blind stitch sewing machine, an oscillatory ridge forming disc having high and low peripheral portions arranged in tandem, a needle reciprocating above the disc, means for reciprocating the needle, means for oscillating the disc in timed relation to the needle reciprocations to thereby successively present the high portion of the disc to the needle to maintain constant the effective depth of needle penetration, and manually controlled means for effecting the presentation of the high portion of the disc to the needle during certain cycles and the presentation of the low portion of the disc to the needle during other cycles to thereby vary the effective depths 20 of needle penetrations.

38. In a blind stitch sewing machine, the combination with a main shaft, of an oscillatory shaft, a ridge forming disc fixed thereto and having high and low peripheral portions arranged in 30 tandem, a needle reciprocating above the disc, means for reciprocating the needle, driving connections between said shafts for oscillating the disc in timed relation to the needle reciprocations to thereby successively present a high portion 35 of the disc to the needle to maintain constant the effective depth of needle penetration, and manually controlled means associated with said driving connections for effecting the presentation of the high peripheral portion of the disc to the 40 needle during certain cycles and the presentation of the low peripheral portion of the disc to the needle during other cycles to thereby vary the effective depths of needle penetrations.

39. In a sewing machine, the combination with 45 a frame including a base, a standard, an arm extending laterally from the upper end of the standard, and an arm extending forwardly from the other end of the laterally extending arm, of a presser foot fixed to the front end of the forwardly extending arm, a stitch forming mechanism including a needle mounted on the front end of said forwardly extending arm above the presser foot, a substantially horizontal work support disposed in front of the laterally extending 50 arm and having a portion located under said presser foot, means for pivotally mounting the work support on the base, the pivot being located in a vertical plane in rear of the needle, a spring for urging the front portion of the work support 55 upwardly towards the needle, and an adjustable screw mounted in the rear portion of the work support and bearing against a frame portion to variably lower positively the front portion of the work support against the tension of said spring. 60 65

CHARLES W. MUELLER.
